(57) **CLAIM**

We claim the ornamental design for a tracking device mount, as shown and described.

DESCRIPTION

FIG. 1 is a perspective view of a tracking device mount.

FIG. 2 is a front elevation view thereof, the rear elevation view is identical to the front elevation view.

FIG. 3 is a top plan view thereof.

FIG. 4 is a bottom plan view thereof; and,

FIG. 5 is a right-side elevation view thereof, the left-side elevation view is identical to the right-side elevation view.

1 Claim, 5 Drawing Sheets
